(57) **CLAIM**

The ornamental design for a media preparation apparatus, as shown and described.

DESCRIPTION

FIG. 1 is a front, left, top perspective view of a media preparation apparatus shown with a transparent front panel cover showing the new design.

FIG. 2 is a front elevation view of the media preparation apparatus of FIG. 1.

FIG. 3 is a rear elevation view of the media preparation apparatus of FIG. 1.

FIG. 4 is a rear, right, top perspective view of the media preparation apparatus of FIG. 1.

FIG. 5 is a rear, left, top perspective view of the media preparation apparatus of FIG. 1.

FIG. 6 is a right side elevation view of the media preparation apparatus of FIG. 1.

FIG. 7 is a left side elevation view of the media preparation apparatus of FIG. 1.

FIG. 8 is a top plan view of the media preparation apparatus of FIG. 1.

FIG. 9 is a bottom plan view of the media preparation apparatus of FIG. 1.

FIG. 10 is a rear, left, bottom perspective view of the media preparation apparatus of FIG. 1.

FIG. 11 is a front, right, bottom perspective view of the media preparation apparatus of FIG. 1.

FIG. 12 is a front, right, top perspective view of the media preparation apparatus of FIG. 1 shown without the front panel cover.

FIG. 13 is a front, left, top perspective view of the media preparation apparatus of FIG. 1 shown without the front panel cover.

FIG. 14 is a front elevation view of the media preparation apparatus of FIG. 1 shown without the front panel cover.

FIG. 15 is a rear elevation view of the media preparation apparatus of FIG. 1 shown without the front panel cover.

FIG. 16 is a rear, right, top perspective view of the media preparation apparatus of FIG. 1 shown without the front panel cover.

FIG. 17 is a rear, left, top perspective view of the media preparation apparatus of FIG. 1 shown without the front panel cover.

FIG. 18 is a right side elevation view of the media preparation apparatus of FIG. 1 shown without the front panel cover.

FIG. 19 is a left side elevation view of the media preparation apparatus of FIG. 1 shown without the front panel cover.

FIG. 20 is a top plan view of the media preparation apparatus of FIG. 1 shown without the front panel cover.

(Continued)

FIG. 21 is a bottom plan view of the media preparation apparatus of FIG. 1 shown without the front panel cover. FIG. 22 is a rear, left, bottom perspective view of the media preparation apparatus of FIG. 1 shown without the front panel cover; and, FIG. 23 is a front, right, bottom perspective view of the media preparation apparatus of FIG. 1 shown without the front panel cover.
